(57) **CLAIM**

The ornamental design for a dredging nozzle, as shown and described.

DESCRIPTION

FIG. 1 is a front perspective view of the dredging nozzle of the present invention;

FIG. 2 is a left side elevational view of the invention shown in FIG. 1;

FIG. 3 is a right side elevational view of the invention shown in FIG. 1;

FIG. 4 is a front elevational view of the invention shown in FIG. 1;

FIG. 5 is a rear elevational view of the invention shown in FIG. 1;

FIG. 6 is a bottom plan view of the invention shown in FIG. 1; and,

FIG. 7 is a top plan view of the invention shown in FIG. 1. The broken line illustrations shown in the drawings depict environmental subject matter only and form no part of the claimed design.
